(57) **CLAIM**

We claim the ornamental design for a charger positioning belt, as shown and described.

DESCRIPTION

FIG. 1 is a perspective view of a charger positioning belt according to a first embodiment, with unclaimed portions shown in broken line for illustrative purposes only.

FIG. 2 is a front view of the charger positioning belt depicted in FIG. 1.

FIG. 3 is a back view of the charger positioning belt depicted in FIG. 1.

FIG. 4 is a right side view of the charger positioning belt depicted in FIG. 1.

FIG. 5 is a left side view of the charger positioning belt depicted in FIG. 1.

FIG. 6 is a top view of the charger positioning belt depicted in FIG. 1.

FIG. 7 is a bottom view of the charger positioning belt depicted in FIG. 1.

FIG. 8 is a perspective view of a charger positioning belt according to a second embodiment, with unclaimed portions shown in broken line for illustrative purposes only.

FIG. 9 is a front view of the charger positioning belt depicted in FIG. 8.

FIG. 10 is a back view of the charger positioning belt depicted in FIG. 8.

FIG. 11 is a right side view of the charger positioning belt depicted in FIG. 8.

FIG. 12 is a left side view of the charger positioning belt depicted in FIG. 8.

FIG. 13 is a top view of the charger positioning belt depicted in FIG. 8.

FIG. 14 is a bottom view of the charger positioning belt depicted in FIG. 8.

FIG. 15 is a perspective view of a charger positioning belt according to a third embodiment, with unclaimed portions shown in broken line for illustrative purposes only.

FIG. 16 is a front view of the charger positioning belt depicted in FIG. 15.

FIG. 17 is a back view of the charger positioning belt depicted in FIG. 15.

FIG. 18 is a right side view of the charger positioning belt depicted in FIG. 15.

FIG. 19 is a left side view of the charger positioning belt depicted in FIG. 15.

FIG. 20 is a top view of the charger positioning belt depicted in FIG. 15.

FIG. 21 is a bottom view of the charger positioning belt depicted in FIG. 15.

FIG. 22 is a perspective view of a charger positioning belt according to a fourth embodiment, with unclaimed portions shown in broken line for illustrative purposes only.

FIG. 23 is a front view of the charger positioning belt depicted in FIG. 22.

FIG. 24 is a back view of the charger positioning belt depicted in FIG. 22.

FIG. 25 is a right side view of the charger positioning belt depicted in FIG. 22.

FIG. 26 is a left side view of the charger positioning belt depicted in FIG. 22.

FIG. 27 is a top view of the charger positioning belt depicted in FIG. 22.

FIG. 28 is a bottom view of the charger positioning belt depicted in FIG. 22.

FIG. 29 is a perspective view of a charger positioning belt according to a fifth embodiment, with unclaimed portions shown in broken line for illustrative purposes only.

FIG. 30 is a front view of the charger positioning belt depicted in FIG. 29.

FIG. 31 is a back view of the charger positioning belt depicted in FIG. 29.

FIG. 32 is a right side view of the charger positioning belt depicted in FIG. 29.

FIG. 33 is a left side view of the charger positioning belt depicted in FIG. 29.

FIG. 34 is a top view of the charger positioning belt depicted in FIG. 29.

FIG. 35 is a bottom view of the charger positioning belt depicted in FIG. 29.

FIG. 36 is a perspective view of a charger positioning belt according to a sixth embodiment, with unclaimed portions shown in broken line for illustrative purposes only.

FIG. 37 is a front view of the charger positioning belt depicted in FIG. 36.

FIG. 38 is a back view of the charger positioning belt depicted in FIG. 36.

FIG. 39 is a right side view of the charger positioning belt depicted in FIG. 36.

FIG. 40 is a left side view of the charger positioning belt depicted in FIG. 36.

FIG. 41 is a top view of the charger positioning belt depicted in FIG. 36.

FIG. 42 is a bottom view of the charger positioning belt depicted in FIG. 36.

FIG. 43 is a perspective view of a charger positioning belt according to a seventh embodiment, with unclaimed portions shown in broken line for illustrative purposes only.

FIG. 44 is a front view of the charger positioning belt depicted in FIG. 43.

FIG. 45 is a back view of the charger positioning belt depicted in FIG. 43.

FIG. 46 is a right side view of the charger positioning belt depicted in FIG. 43.

FIG. 47 is a left side view of the charger positioning belt depicted in FIG. 43.

FIG. 48 is a top view of the charger positioning belt depicted in FIG. 43.

FIG. 49 is a bottom view of the charger positioning belt depicted in FIG. 43.

FIG. 50 is a perspective view of a charger positioning belt according to an eighth embodiment, with unclaimed portions shown in broken line for illustrative purposes only.

FIG. 51 is a front view of the charger positioning belt depicted in FIG. 50.

FIG. 52 is a back view of the charger positioning belt depicted in FIG. 50.

FIG. 53 is a right side view of the charger positioning belt depicted in FIG. 50.

FIG. 54 is a left side view of the charger positioning belt depicted in FIG. 50.

FIG. 55 is a top view of the charger positioning belt depicted in FIG. 50.

FIG. 56 is a bottom view of the charger positioning belt depicted in FIG. 50.

FIG. 57 is a perspective view of a charger positioning belt according to a ninth embodiment, with unclaimed portions shown in broken line for illustrative purposes only.

FIG. 58 is a front view of the charger positioning belt depicted in FIG. 57.

FIG. 59 is a back view of the charger positioning belt depicted in FIG. 57.

FIG. 60 is a right side view of the charger positioning belt depicted in FIG. 57.

FIG. 61 is a left side view of the charger positioning belt depicted in FIG. 57.

FIG. 62 is a top view of the charger positioning belt depicted in FIG. 57; and,

FIG. 63 is a bottom view of the charger positioning belt depicted in FIG. 57.

The broken lines depict portions of the article that form no part of the claimed design.
